UNITED STATES PATENT OFFICE.

JAMES F. SHANNON, OF MACOMB, ILLINOIS, ASSIGNOR TO HIMSELF AND
ADOLPHUS W. FALKENTHAL, OF SAME PLACE.

DESIGN FOR A TOOL-HAMMER.

SPECIFICATION forming part of Design No. 20,777, dated May 26, 1891.

Application filed April 27, 1891. Serial No. 390,690. Term of patent 7 years.

To all whom it may concern:

Be it known that I, JAMES F. SHANNON, of Macomb, in the county of McDonough and State of Illinois, have invented and produced 5 a new and original Design for a Tool, of which the following is a specification.

Reference is to be had to the accompanying drawing, forming a part of this specification, in which the figure represents in perspective 10 a tool embodying my new design.

The design consists in the peculiar configuration shown.

The letter A indicates the head, and B the handle, of the tool. The lines of the head A, 15 at the flat sides α and at the side toward the

handle, merge into the lines of the latter, and at one side of the said handle the lines of the head range about at right angles to the handle and terminate in a flat face, as indicated at a' . At the opposite side of the handle B 20 the lines of the head A curve inward in the direction of the handle, and all converge to the common inwardly-curved point a^2 .

I claim—

The design for a tool herein shown and described. 25

JAMES F. SHANNON.
